UNITED STATES PATENT OFFICE

HAROLD S. WATSON, OF BROOKLYN, NEW YORK

ASH TRAY

Application filed March 25, 1931. Serial No. 525,227.

The present invention relates to new and useful improvements in smokers' appliances, and more particularly it pertains to a new and novel ash tray.

5 In ash trays as generally constructed, means for supporting a lighted cigarette or cigar is provided as the lighted cigarette or cigar continues to burn, it overbalances and falls off of the support. In this type of device, the falling cigarette invariably lands upon the table or other article of furniture upon which the ash tray is supported, and often does serious damage thereto in the form of burns.

10 15 It is the primary object of the present invention to provide an ash tray in which a lighted cigarette or cigar may be supported and when the same falls off of its support, it will be received in a tray and prevented 20 from falling upon the support by which the ash tray is carried.

A further object of the invention resides in the provision of a novel construction which is cheap to manufacture, efficient in operation 25 and ornamental in appearance.

With the above and other objects in view, reference is had to the accompanying drawing forming a part of this application and in which;

30 Figure 1 is a perspective view of a device constructed in accordance with the present invention,

Figure 2 is a sectional view taken on the line 2—2 of Figure 1,

35 Figure 3 is a sectional view taken on the line 3—3 of Figure 1, and

Figure 4 is a fragmentary top plan view.

Referring more specifically to the drawing, 40 the device comprises a tray A having a bottom wall 10 and angularly disposed side walls 11 projecting upwardly therefrom.

The reference character B designates a pedestal and this pedestal is carried by the bottom wall 10 of the tray and is preferably 45 centrally located with respect to the tray and its bottom wall. The pedestal B has a base portion 12 and a head portion 13 the intermediate portion 14 being preferably contracted. The base portion 12 and the head portion 13 are preferably of rectangular

form, and in the present illustration of the invention, the head portion 13 is of slightly larger dimension than the base portion 12.

The top wall of the pedestal B is provided with a plurality of diagonally extending 55 grooves or the like 16 which groove forms seats for the reception of cigarettes, cigars or the like, and this upper face of the pedestal B is defined by a beveled or angular wall 18 in which the ends of the seats terminate as 60 best illustrated in Figures 1 and 4.

The beveled or angular wall 18 heretofore described plays a very important part in the present device as will be hereinafter pointed out. By reference to Figure 4 in 65 which a lighted cigarette is shown as resting in one of the seats formed by a groove 16 it will be noted that as soon as the cigarette which is designated D burns sufficiently to cause its outer end to overbalance the 70 remainder, the same will topple over the beveled or angular wall 18 and will fall immediately to the bottom of the pedestal and within the confines of the side walls of the tray 10. This falling immediately to the bottom 75 of the pedestal is occasioned by reason of the angular position or the bevel of the wall 18 since in falling, the cigarette will take a sidewise motion rather than an end over end motion as would be 80 the case if the wall 18 were not beveled and if the seats formed by the grooves 16 extended at right angles to the wall 18 or transversely of the upper face of the pedestal B instead of diagonally thereof as illustrated.

85 Thus it will be apparent that the present invention provides a new and novel smoker's appliance in which cigars, cigarettes or the like may be placed upon a suitable support in burning conditions and that when the same topples from said support, reception thereof by a tray is assured, thus removing all possibility of doing damage to the support upon which the tray may be carried as heretofore pointed out, which is the result of 90 this action in connection with ash trays and the like as commonly formed or constructed.

95 While the present invention has been herein illustrated in a preferred form, it is to be 100 understood that the invention is not to be

limited to the specific construction herein illustrated, and that it may be practiced in other forms without departing from the spirit thereof.

5 Having thus described the invention, what is claimed as new and what it is desired to secure by Letters-Patent of the United States, is;

10 A device of the character described comprising a tray, a pedestal arranged centrally of the tray and upstanding therefrom, a beveled wall defining the edge of the upper face of said pedestal, and a plurality of seats upon the upper face of the pedestal, each seat consisting of a groove extending angularly across the upper face of the pedestal and terminating at its ends in said beveled wall.

15 In testimony whereof I affix my signature.
HAROLD S. WATSON.
